UNITED STATES PATENT OFFICE.

FRANK ARTHUR KING, OF HITHER GREEN, LONDON, AND FREDERICK REYNOLDS, OF WALKERVILLE-ON-TYNE, ENGLAND.

VAPOR ELECTRIC LAMP.

Application filed May 12, 1922, Serial No. 560,390, and in Great Britain November 29, 1921.

This invention relates to mercury, and other vapor, electric lamps of the atmospheric type, of the general character, for instance, of lamps such as are described in the 5 specifications of British Letters Patent Nos. 5,596 and 21,834 A. D. 1908, No. 14,587 A. D. 1911, No. 129,022 A. D. 1919, and particularly No. 172,666 A. D. 1920, the object of the present invention being to provide means 10 by which the mercury, or other metallic substance, to be employed in the lamps, can be readily introduced and withdrawn so that the lamps can be transported from place to place without containing mercury, or the 15 like, and the mercury, or the like, be introduced, by even an inexperienced person, at the place where the lamps are to be used.

According to this invention the lamp is provided, in any convenient position, or positions, with an opening, or openings, of sufficient size to allow of the convenient introduction and removal of the mercury, or the like, which we will refer to as mercury. The 20 said opening, or openings, may, for example, be at the end, or ends, of a small tube or neck, or of small tubes, communicating with the interior of the lamp. For this opening, or for each of these openings, a device for closing it such as a plug, or stopper, (we 25 will refer to it as a plug) is provided, which plug can be made of fused quartz-glass, or of ordinary glass, or of other suitable material, and be ground to fit into the ground opening which it is to close. Each plug can, 30 if necessary, be provided with additional means to keep it securely in position after the mercury has been introduced into the lamp, and any necessary conductor can be passed through the plug, or each plug, and 35 any suitable contact, or contacts, or other device in connection with the lamp, can be combined with the plug; for instance, a contact may be included to complete any required circuit, or circuits, when the plug is, 40 or plugs are, in place; or the plug may carry the U-shaped tube described in the specification and shown at 13 in the drawing of the aforesaid British Patent 172,666, to allow, 45 of the escape of air from the lamp when it is being started; or the plug may be made as part of the tubular projection and small container for the mercury with which contact is made for putting the heater of the lamp out of circuit when the lamp has been 50 started; or the plug can be simply perforated 55

to allow of the escape of air when the lamp is started.

The accompanying drawing represents, in section, sufficient of one end of a mercury vapor electric lamp to explain various ways in which means, in accordance with this invention, can be applied to lamps such as are described in the specification of the aforesaid British Patent No. 172,666. In the several Figures, 1, 2 and 3, corresponding parts are marked with the same reference letters. Fig. 4 is a plan view of the heater *h* for starting the lamp.

Referring first to Figure 1:—The opening at *a* for the introduction and withdrawal of mercury, is at the upper end of the tubular neck or projection *b* which communicates with the interior of the extension *c*, which holds the mercury which is displaced from the mercury receptacle at one end of the lamp when it is put into action. The opening, at *a*, of the tubular projection *b*, is provided with a plug *d*, which may be presumed to be made of quartz glass the said opening *a* and the said plug *d* being ground to give a good closure.

In Figure 2 is shown a modification wherein the plug *d*, and the U-shaped tube *e*, for the escape of air when the lamp is started, are made in one piece the plug portion *d*, fitting into the opening *a*, at the upper end of the tubular projection, or extension, *b*, the plug portion *d* being made hollow, with an opening *f* at top, so that the interior of the plug portion *d*, and the opening *f*, constitute a continuation of the air-passage through the U-shaped tube *e*.

Figure 3 shows a modification wherein the plug *d*, is hollow and is formed as part of the tubular projection *g* and small container, or bulb, *g*, which is for containing the mercury with which contact is made when the lamp is started. In this case, if desired, the air, when the lamp is started, can escape through the openings in the bulb *g*, and out by the opening *f*, from the interior of the plug portion *d*, or an independent air-escape passage can be provided. At *h* we have indicated cement which may be used to make a good joint.

As before stated, a small opening for the escape of air may be made through the plug *d*, Figure 1, if desired.

What we claim is:—

A vapor electric lamp of atmospheric type 110

having a neck forming a tubular opening from the receptacle for the material vaporizable when the lamp is put into action in combination with a removable plug of the same material as that of the neck adapted to close the opening of said neck and to permit ready removal of the vaporizable material when desired, said plug including a tu-

bular projection containing an electrical conductor and also including a small container suitable for the vaporizable material contact.

In testimony whereof we have signed our names to this specification.

FRANK ARTHUR KING.
FREDERICK REYNOLDS.
